(57) **CLAIM**

The ornamental design for a jug-shaped bag, as shown and described.

DESCRIPTION

FIG. 1 is a top plan view of a jug-shaped bag in an uncinched condition, having a top surface with shading indicating the first preselected fabric and a carry strap

FIG. 2 is a rear perspective view of FIG. 1;

FIG. 3 is a front perspective view of FIG. 1;

FIG. 4 is a bottom perspective view of FIG. 1;

FIG. 5 is a top perspective view of FIG. 1;

FIG. 6 is a front perspective view of a jug-shaped bag as in FIG. 3, now shown in a cinched condition;

FIG. 7 is a rear perspective view of a jug-shaped bag as in FIG. 2, now shown in a cinched condition; and,

FIG. 8 is a front perspective view of a jug-shaped bag as in FIG. 1, now shown with an adjustable carry strap.

The broken line showing of hardware (e.g., draw cord, buckles) as well as the position of the hardware relative to the claimed design and any other broken lines are to show environment only and are not part of the claimed design.
